US0D1027610S

(12) **United States Design Patent** (10) **Patent No.:** **US D1,027,610 S**
(45) **Date of Patent:** **** May 21, 2024**

(54) **CARGO SECUREMENT DEVICE**

(71) Applicant: **Raul Jimenez-Rosario**, Milwaukee, WI
(US)

(72) Inventor: **Raul Jimenez-Rosario**, Milwaukee, WI
(US)

(**) Term: **15 Years**

(21) Appl. No.: **29/778,442**

(22) Filed: **Apr. 13, 2021**

(51) **LOC (14) Cl.** **08-07**

(52) **U.S. Cl.**

USPC **D8/339**

(58) **Field of Classification Search**

USPC D8/330, 339, 340, 349, 352-356, 363,
D8/364, 366-371, 373, 376, 377, 380,

D8/381, 384; D12/41, 42, 48, 106, 223

CPC E05B 83/08; E05B 81/08; E05B 39/005;
E05C 19/003

See application file for complete search history.

(57) **CLAIM**

The ornamental design for a cargo securement device, as shown and described.

DESCRIPTION

FIG. 1 is an upper left perspective view of the cargo securement device showing my new design;

FIG. 2 is a top view thereof;

FIG. 3 is a bottom view thereof;

FIG. 4 is a left side view thereof;

FIG. 5 is a right side view thereof; and,

FIG. 6 shows the cargo securement device of the present design in a representative environment.

Those elements shown in broken lines are for environmental illustration only and form no part of the claimed design.

1 Claim, 6 Drawing Sheets
